[57] CLAIM

The ornamental design for a flower pot cover, substantially as shown and described.

DESCRIPTION

FIG. 1 is a top plan view of the flower pot cover showing our new design with the transparent inner layer partially cut away to show the textured pattern which is understood to repeat across the entire inner surface of the outer layer.

FIG. 2 is a front elevational view thereof.

FIG. 3 is a rear elevational view thereof.

FIG. 4 is a side elevational view thereof.

FIG. 5 is a side elevational view similar to FIG. 4, but showing the side opposite that shown in FIG. 4.

FIG. 6 is a bottom plan view thereof, the pattern which is partially shown is understood to repeat across the entire outer surface.

FIG. 7 is an enlarged plan view of the textured pattern shown in FIGS. 1 and 6.

The flower pot cover has no substantial thickness.
